UNITED STATES PATENT OFFICE

PHILIP ADOLPH KOBER, OF EVANSTON, ILLINOIS, ASSIGNOR TO G. D. SEARLE & CO., OF CHICAGO, ILLINOIS, A CORPORATION OF ILLINOIS

ALKALINE BISMUTH TARTRATE SOLUTION

No Drawing.

Application filed May 1, 1928. Serial No. 274,350.

This invention relates to the preparation of aseptic solutions for subcutaneous injection, and more particularly to the preparation of solutions of alkali metal bismuth tartrates adapted for intramuscular injection.

The use of bismuth compounds in the treatment of syphilis is of considerable importance and an improved process for the manufacture of alkali metal bismuth tartrates is described in my Patent No. 1,663,201, issued March 20, 1928.

It is an object of the present invention to provide a process for dissolving and holding in solution tartrates of bismuth and in particular tetra bismuth tartrates.

A further object is to prepare a solution of alkali metal bismuth tartrates and a local anesthetic so selected that there will be no chemical action between the components of the solution with the production of reaction products that are insoluble or otherwise undesirable.

Sometimes aqueous solutions of the usual bismuth tartrates are administered intravenously, but most physicians prefer to inject these preparations intramuscularly, which treatment for best results requires the following conditions:

1. The solution should be an aqueous one, in order that the compound may be readily absorbed.

2. The solution must be compatible with blood, that is, it must not react upon or precipitate blood proteins or other constituents.

3. It should be painless on injection into the muscles.

4. It must be stable enough to permit absorption and general distribution in the body before the metabolic processes oxidize or otherwise alter the bismuth preparation.

These conditions have been so difficult to fulfil, especially the third, that most bismuth preparations are put up as suspensions in oil, which makes the absorption of the bismuth undesirably slow.

Now, I have been able to prepare, and it is a further object of the invention to provide a solution of alkali metal bismuth tartrates which, after thousands of experiments, has

been proven to possess all four of the above mentioned characteristics.

I have discovered that strong, that is, hypertonic solutions of cane sugar or sucrose are not only compatible with alkali bismuth tartrates, but that these solutions render the tartrate more stable and less irritating and damaging to the muscular tissues.

Isotonic solutions (about 5%) of sugars have been used for menstrua of metallic bismuth suspensions and a few alkali metal bismuth tartrates of low bismuth content (50% or less) in order to make the solution isotonic to blood; but apparently its protective or "buffer" action was not known or recognized, for to get complete "buffer" action these solutions are not strong enough; 20 to 50% solutions are required for this stabilization. By the word "buffer" it is to be understood that I refer to the general 70 stabilizing and solvent effects of the sugar, which makes the tartrate less likely to precipitate upon contact with the blood.

Other sugars than sucrose, such for example as glucose, may be similarly employed, 75 but, while my invention contemplates the use of any sugar in hypertonic solution, my preferred form of the invention embraces sucrose.

While this action of the sugars makes the 80 injection intramuscularly easily tolerated by the patient, it also makes its administration safer intravenously, as it makes the bismuth compound less active chemically until it has been generally distributed throughout the 85 body and metabolized.

In addition to make the alkali metal bismuth tartrate stable in solution and non-irritating or damaging to the tissues, it was necessary to find a local anesthetic to alleviate 90 the pain of injection into the muscular tissue. In selecting an anesthetic, it is of course necessary to find one which is first, soluble in water or the menstruum employed; and second, one which will not react with the other 95 substances present to form reaction products that are insoluble or otherwise objectionable. Many local anesthetics were tried; many are so insoluble in water that they serve no useful purpose; others have acid groups at- 100

tached which I found reacted with the alkali metal bismuth tartrates on standing to form insoluble gelatinous precipitates, making the product obviously unsuitable for injection.

After much experimentation, benzyl alcohol was found to be a suitable local anesthetic, being soluble and having no action on long standing upon the alkali metal tartrates. Procaine hydrochloride was also found useful as a local anesthetic for these alkali metal bismuth tartrate preparations as the following illustration shows. To an aqueous solution of alkali metal tartrate, for example, sodium bismuth tartrate, was added 1% procaine hydrochloride crystals; on dissolving the crystals precipitated the bismuth compound; but in making the solution hypertonic with sugar, the precipitate dissolves to a perfectly clear solution, which shows the useful protective and stabilizing action of the sugar.

Other local anesthetics may be found or developed for fulfilling the requirements of this purpose, in that they are soluble and do not react with alkali metal tartrates, without deviating from the spirit of the present invention.

In practice I prefer making such a solution for intramuscular and other administrations as follows:

75 grams of alkali metal bismuth tartrate, preferably sodium bismuth tartrate, are dissolved in 750 cc. of water to which is added 1250 gm. of sucrose dissolved in 3000 cc. of distilled water. After shaking and mixing, 100 cc. of benzyl alcohol are added and the solution again thoroughly shaken until all of the benzyl alcohol is dissolved. The solution is then diluted to a volume of 5000 cc. with distilled water, and is then filtered with the aid of a little talc. The solution is then siphoned off into ampoules which are hermetically sealed, or into other vessels such as vials suitable for sterilizing and that keep the solutions sterile. After sterilization the solutions are ready for injection.

I claim:

1. An aqueous hypertonic sugar solution containing alkali metal bismuth tartrate, said solution being compatible with blood, and sufficiently stable to permit absorption and general distribution in the body before substantial alteration of said solution takes place.

2. An aqueous hypertonic sugar solution containing alkali metal bismuth tartrate and benzyl alcohol, said solution being compatible with blood, substantially painless on injection, and sufficiently stable to permit absorption and general distribution in the body before substantial alteration takes place.

3. An aqueous hypertonic sugar solution containing alkali metal tetra bismuth tartrate, said solution being compatible with

blood, and sufficiently stable to permit absorption and general distribution in the body before substantial alteration of said solution takes place.

4. An aqueous hypertonic sugar solution containing alkali metal bismuth tartrate and one of the group comprising benzyl alcohol and procaine hydrochloride, said solution being compatible with blood, substantially painless on injection, and sufficiently stable to permit absorption and general distribution in the body before substantial alteration takes place.

5. An aqueous hypertonic sugar solution made with sucrose and containing sodium bismuth tartrate, said solution being compatible with blood, and sufficiently stable to permit absorption and general distribution in the body before substantial alteration of said solution takes place.

PHILIP ADOLPH KOBER.
